US00D831095S

(12) **United States Design Patent** (10) **Patent No.:** **US D831,095 S**
Deng (45) **Date of Patent:** **** Oct. 16, 2018**

(54) **PROJECTOR**

(71) Applicant: **Feiyue Deng**, Sichuan Province (CN)

(72) Inventor: **Feiyue Deng**, Sichuan Province (CN)

(**) Term: **15 Years**

(21) Appl. No.: **29/601,199**

(22) Filed: **Apr. 20, 2017**

(30) **Foreign Application Priority Data**

Mar. 14, 2017 (CN) 2017 3 0072777

(51) **LOC (11) Cl.** **16-02**

(52) **U.S. Cl.**

USPC **D16/230**; D16/225

(58) **Field of Classification Search**

USPC D16/221, 225, 230-231, 234; D21/514

CPC G03B 21/145; G03B 21/14; G03B 21/16;

G03B 21/12; G03B 21/001; G03B

21/003; G03B 21/00; G03B 21/28

See application file for complete search history.
